APPARATUS FOR COLD REDUCING
METAL BARS

Gustaf L. Fisk, New Fairfield, Conn.

Application October 25, 1945, Serial No. 624,344

15 Claims. (Cl. 271—2.1)

1

This invention relates to the cold-working of metal bars of a great variety of sections, commonly known as merchant bars and shapes, whereby they may be finished to precise dimensions within close tolerances, and with improved physical properties.

In my co-pending application Serial No. 531,724, filed April 19, 1944, for Method and Apparatus for Cold-Rolling Metal Bars, which has been abandoned and superseded by my copending continuation application Serial No. 226,467, filed May 15, 1951, I disclosed and claimed the use of leaders and power-driven tension rolls to pull the bars into the roll passes, and to maintain the bars under tension while reducing their section to desired size. I also disclosed and claimed guiding means to keep round bars from turning on their own axes in the passes of a cold mill. Also disclosed and claimed in said application is the cold-drawing of bars, by aid of leaders and power-driven tension rolls to pull the bars into and through the dies.

The pull of such tension rolls, however, is limited by the effective pressure zone and by the maximum unit loads that can be carried by the materials of the belts and tires employed. To fully realize the advantages of the scheme involved, a much greater pulling capacity is desirable. For instance, the reduction of a $1\frac{1}{16}$ " diameter round of medium tensile strength to 1" diameter round by cold-drawing through dies may require a pull of 15,000 lbs.; a figure beyond the practical capacity of a single pair of tension rolls.

So far as I am aware, no endless traction device has heretofore been available for frictionally gripping a highly finished steel merchant bar to exert a pull thereon close to its elastic limit and without injury to its surface. Such tension is highly desirable in that it permits heavy bar deformation without rapid hardening of the metal. Such devices as have been developed for desired tension are for wire products, strip and sheet metal that can be bent around a drum or coiled without injury. My invention, on the other hand, pertains to merchant bars which must be furnished in straight lengths and can not be bent over a drum without injury to their structure.

To meet the needs of the trade as outlined above, I have invented a traction apparatus which grips a bar over any reasonable predetermined length and, with the aid of belts of elastic material, furnishes necessary pressure on the bar without injury to its surface, for pulling the

2

bar by friction up to its elastic limit. The necessary pressure is exerted through the medium of elastic cushions immediately supporting idler runways for traction chains, which in turn support the belts and transmit the power from the driving sprockets to the belts. The pressure on the bar is controlled by adjusting the position of the idler runways and their supporting cushions, to cause the bar to compress the cushions on its passage through the apparatus. By these means I have provided a traction apparatus of adequate capacity. When only limited traction is required for sizing of bars, then the tension rolls of said copending application may be used or their traction augmented in the manner herein disclosed.

It is the object of the present invention to provide a novel traction apparatus of adequate pulling capacity.

It is a further object to eliminate the need for leaders, by using such a traction apparatus in conjunction with suitable guides to push the successive bars into a roll pass or die, as the case may be, and another traction apparatus on the delivery side to exert pull on the emerging bars.

Reciprocating machinery has been developed to grip the forward end of a bar and push it through a die, so it can be gripped by the reciprocating jaws of a draw-bench. As compared to this practice the present invention provides for continuous cold-drawing, where each bar immediately follows its predecessor, by aid of one-way continuously operating bar entering and drawing machinery.

Another object of the present invention is to use a traction apparatus on the entry side of a roll pass or a die to furnish back tension on the bar during its reduction, after this traction apparatus has served to push the forward end of the bar into position for working engagement with a traction apparatus on the delivery side.

Another object in cold-rolling from hot-rolled commercial rounds, which are of approximately circular section, is to hold the commercial rounds in the elastic grip of a traction apparatus to keep them from turning on their own axes.

Still another object in case of major reductions by cold-rolling, is to provide for profitable use of such ends of the cold-rolled bars as may be over-size and out of shape due to rolling without benefit of tension.

For a complete understanding of the invention and the novel features thereof, reference is made to the following detailed description and the accompanying drawings. The latter illus-

trate the power-driven traction apparatus and diagrammatically the preferred practice of my invention as applied to cold-rolling, cold-drawing and sizing of bars, as well as guiding equipment which I prefer to employ. In the drawings:

Figure 1 is a view in elevation and partly in vertical section, showing my traction apparatus;

Figure 2 is a vertical section on line II—II of Figure 1;

Figure 3 is an enlarged view partly in elevation, and partly in vertical section on line III—III of Figure 1, showing end view of roller runway for a traction chain, shafting for gripping movement of a roller runway, and a double-wedge adjusting rig;

Figures 20 and 21 are enlarged side views and partly vertical sections and show respectively entry and delivery guide equipment in relation to other parts of the traction apparatus of Figures 1 to 11 inclusive;

Figures 22 and 23 are a plan view and a horizontal section respectively, corresponding to Figures 20 and 21.

Figure 24 is a section on line XXIV—XXIV of Figure 20; and

Figure 25 is an enlarged partial section on any of lines XXV—XXV in Figures 16, 17, 18, 19, 22 and 23.

Referring in detail to the drawings and for the present to Figures 1 through 3 and Figure

11, two co-operating endless chains 1 and 1', trained over driving sprockets 2 and 2' and idler sprockets 3 and 3', engage the belts 4 and 4' which can be brought to contact a bar 5 to establish traction thereon by friction. Co-operating chain drives are common mechanical elements and need no further explanation, but the apparatus whereby their traction is transmitted to a finished metal bar without injury to its surface, so as to create a pull on the bar equivalent to or near its elastic limit, involves novel features now to be explained.

In the space between the driving sprockets 2, 2' on one hand and the idler sprockets 3, 3' on the other, and where the belts 4, 4' run in close proximity to one another, the chains 1, 1' are backed up by runways 6 and 6' of a series of idler rollers 7 and 8, journaled in anti-friction bearings 9 and individually cushioned by rubber sandwiches 10 on movable girders 11 and 11'. The motions of these girders are simultaneous and towards or from the pass line of the apparatus, to cause the belts 4, 4' to grip or release a bar in transit 5.

The bottom girder 11, at both ends, is carried in bearings 12 on crank shaft 13, which is journaled in bearings 14 of a carriage 15 with lugs 16, resting on wedges 17 and maintained central with respect to the pass line of the apparatus by contact with lugs 18 on the main housing 19. The top girder 11' is similarly mounted by aid of corresponding items 12', 13', 14', 15', 16', 17', and 18', but the entire assembly of carriages 15', crank shafts 13' and girder 11' with runway 6' is suspended by spring balance from the main housing 19. This spring balance is accomplished by aid of pins 20 in girder 11', eye rods 21, pivot blocks 22 journaled in the main housing 19 at 23, compression springs 24, washers 25 and nuts 26.

The girders 11, 11' have ways 27 and 27' in which cross heads 28 and 28' are fitted to slide. These cross heads are mounted on eccentrics 29 and 29' on shafts 30 and 30', journaled in stationary bearings 31 and 32 and 31' and 32'. Miter gears 33 and 33' and shaft 34 connect the shafts 30, 30' for simultaneous and equivalent turning motions, effected by motor 35 driving shaft 30 through pinion 36 and gear 37.

It will be apparent that the operation of motor 35 will turn eccentrics 29, 29' and cause cross heads 28, 28' to force a movement of girders 11, 11' in longitudinal direction. But this movement will cause the crank shafts 13, 13' to turn in bearings 14, 14' and move the girders 11, 11' with runways 6, 6', and thus the chains 1, 1' supported thereon, towards or from the pass line, so as to make the belts 4, 4' grip or release a bar 5 at the will of the motor operator.

Provisions to allow for these chain and belt movements will be referred to hereinafter. The spring balance already described is designed to allow for required movements of the top girder 11' and to balance approximately twice the weight of the parts suspended, to firmly hold this girder in place.

The bar-gripping drive just described is controlled by limit switch to provide a fixed gripping motion, determined by eccentrics 29, 29' and crank shafts 13, 13'. To allow for different sizes of bars and to vary the pressure applied to the bars, adjusting rigs are provided to vary the position of the gripping machinery, as will now be explained. To this end, the wedges 17 are furnished with and hold nuts 38 and 39

against turning (Figure 3). These nuts have right and left hand threads respectively and travel on a screw 40 at the same rate but in opposite directions, and thus move the wedges towards or from one another. Each of the two screws 40 (Figures 1 and 3) is anchored in longitudinal direction in a bearing 41 of the main housing 19, so that the wedges 17 in their movements remain centered with respect to the pass line of the traction apparatus. Each of the two screws 40 is connected by means of gearing 42 and 43 to a shaft 44 (Figures 1, 2 and 3), and this shaft has a worm-wheel 45 engaging a worm 46 for operation by hand-wheel 47.

This manually operated adjusting rig provides for the movement of runway 6 towards or from the pass line, as required, while maintaining the runway parallel with the pass line. A similar rig actuating wedges 17' and including corresponding items 38', 39', 40', 41', 42', 43', 44', 45', 46' and 47', serves for hand adjustment of runway 6' with respect to the pass line. Items 38', 39' and 41' are not visible in the drawings but their location and construction are evident from those of corresponding items 38, 39 and 41. These adjusting rigs thus provide for accurate setting of pass opening, to obtain desired gripping force on a bar 5 when the gripping drive is operated.

The chains 1, 1', in their travel from driving sprockets 2, 2' to idler sprockets 3, 3', are supported on idler rollers 48 and 48', which are journaled in anti-friction bearings 49 and 49' and cushioned by rubber sandwiches 50 and 50' for support on the main housing 19.

The detailed construction of chains 1, 1' is illustrated by Figures 4 through 6. The chain blocks 51 and 52, which form the links of the chain when assembled on pins 53, fit one another with small clearances 54 to provide a nearly continuous support for belts 4, 4' in longitudinal direction, while these belts are solidly supported on the individual chain blocks and contained within their guiding ribs 55 and 56. The pins 53 are fastened to chain blocks 51 by rivets 57, while chain blocks 52 are free to pivot on these pins. The pitch 58 of the chain is selected to provide apertures 59 between the chain blocks 52 to fit the teeth 60 of the sprockets. On the inside of the endless chains, each chain block has a projecting ridge 61 which fits corresponding grooves 62 in the idler rollers 7, 8, 48 and 48' and serves to steer the chains centrally of the pass line on runways 6, 6'.

The bearings 9 for rollers 7 and 8 of runways 6, 6', are individually cushioned in a manner now to be explained with particular reference to Figures 7 through 9. A close spacing of these rollers is desirable to lend continuous support to the individual blocks 51 and 52 of chains 1, 1', as they pass over the runways 6 and 6'. To this end, the bearings 9 on either side of each runway have been staggered, to place the bearings for rollers 7 in one row and those of rollers 8 in another row; accomplished by lengthening the shafts of rollers 7 to suit. Each bearing is supported on what is commonly known as a rubber sandwich 10, which in this case consists of a cushion 63 of rubber or rubber-like material, plates 64 and 65 and bolts 66, all bonded together by suitable vulcanizing and readily obtainable from manufacturers of rubber goods. The several sandwiches are fastened to girders 11, 11' by means of tap bolts 67 and spring washers 68, and the bearings 9 are secured to the

individual sandwiches by aid of nuts 69 and spring washers 70.

The individual cushioning of the bearing 9 prevents overloading of any of the rollers 7 and 8 or their bearings. To illustrate, assume that the manually operated adjusting rigs, already described, have been set for a given size of bar, to cause a deflection of the rubber sandwiches 10 corresponding to a total load of 50,000 lbs. on each of the runways 6 and 6' when the bar is gripped by operating motor 35. Assume that the driving sprockets 2, 2' are operating chains 1, 1' with belts 4, 4', to pull the bar through the traction apparatus. With twenty out of twenty-one rollers effective in each runway 6 and 6' (Figures 1 and 11), the load carried per roller figures 2,500 lbs., or 1,250 lbs. per bearing 9. The roller counted not effective is the one next to the driving sprocket, which has to sustain the load incidental to the angularity of the chain pull by the sprocket with respect to the direction of chain travel on the runway. As the rear end of the bar passes through the traction apparatus, the loads on the individual rollers are removed one by one, while the remaining rollers, still deflected by the bar, carry their normal loads only, controlled by the setting of the adjusting rigs.

The chain drives, rollers, bearings and rubber sandwiches involved in a machine of the capacity above referred to can readily be furnished by manufacturers, and traction requirements rather than limitations of machine elements will define the apparatus and capacity best suited to any particular purpose.

Belts 4, 4', shown in cross section in Figure 10, are preferably made of neoprene or other oil-resisting rubber or rubber-like material. Part of the belt thickness is made up of layers of duck 71 and so called friction rubber 72, and the balance of a layer of rubber 73 grooved at 74 to form a pass for a bar 5. Although the groove 74 is made to fit a particular size of bar, the same set of belts may be used for several sizes. As an example, it is my intention to use one set of belts for rounds from $\frac{1}{2}$ " to 1" in diameter. If the width of effective belt contact on a $\frac{3}{4}$ " diameter bar be taken at $\frac{1}{2}$ ", then the contact area per belt for a traction apparatus of the capacity above referred to, with a runway length of 50', figures 25 square inches. This gives an average unit pressure of 2,000 lbs. per square inch, which appears entirely feasible and practical for the belting material I have proposed. Taking the friction coefficient of neoprene on a smooth steel bar at .20, the total traction capacity of the two belts of the apparatus figures 20,000 lbs.

The novel tire, shown in Figures 12 through 14B, has the purpose to increase the traction capacity of the tension rolls of my co-pending application above referred to. Except for the tires, the roll centers, and the cross section and material of the belts, there is no change in construction of these tension rolls.

Cushions 75 of rubber or rubber-like material and their supports 76, preferably of steel, are bonded together to form segments 77. Such segments are fitted to the roll center 78 to form two complete circles and are secured in this position by bolts 79, to form a flexible tire element. The tire tread is formed by an endless chain 80 of construction shown in Figures 14A and 14B, and traction on a bar is exerted by aid of belts 81 of rubber or rubber-like material and of same cross section as that shown in Figure 10. Retain-

ing rings 82 are fastened to the roll center 78 by bolts 83 and serve to limit the side-wise expansion of cushions 75 under load. This expansion can be further limited by insertion of shims 84 indicated in dotted lines.

It is a well known fact that rubber is practically non-compressible and that its deflection and load carrying capacity in one direction are contingent on space for expansion in other directions. It is my purpose to take advantage of these characteristics by allowing the rubber cushion to deflect freely until a pressure zone 85 of suitable length has been established, and then to limit further expansion in one direction so as to increase the load carrying capacity of the tire 15 beyond that corresponding to free expansion.

The application of my traction apparatus and and/or traction rolls to the art of cold-reducing metal bars is aided by guides, indicated in Figures 15 through 19 and more fully illustrated in 20 Figures 20 through 25.

For a clear understanding of the functions of the guides shown in Figures 20 through 24, I now explain the preferred operation of a traction apparatus, indicated generally at 86 in Figure 15, in gripping a bar to exert traction thereon. With the bar gripping mechanism in "off" position, the adjusting rigs are set for desired gripping force on the size of bar to be handled. The sprocket drive is then started to set the chains 4, 4' in motion and cause the belts 4, 4' to travel at desired bar delivery speed. The bar may now be fed to the apparatus by hand or mechanically, but in either event entry guides 87 will serve to direct its forward end to the pass line, by virtue of bell-mouth 88, guiding surfaces 89 and idlers 90. In feeding the bar further into the apparatus, its forward end passes beyond the entry guides but is restrained from moving up or down by the belts 4, 4', which travel in close proximity to the bar but so far exert no pressure on it. Delivery guides 91 have guiding surfaces 92, which allow for a limited deflection of the end of the bar up or down. Should the belt clearance be sufficiently large, however, to permit the bar to leave the grooves 74 in the belts, then its forward end may deflect in sidewise direction to strike guiding surfaces 93 of bellmouth 94, to again be directed to the pass line. When the forward end of the bar reaches idlers 95 and is thus held accurately to the pass line by delivery guides 91 as well as entry guides 87, the bar gripping drive is operated and the predetermined traction applied to the bar, now caused to travel at the predetermined delivery speed.

The idlers 90 and 95 are journaled in anti-friction bearings 96 and facilitate bar passage with a minimum of guide clearance. The guides 87 and 91 are held in guide boxes 97 by bolts 98 with nuts 99, and their position is adjustable by aid of shims 100. The guide boxes are supported on rest bars 101 and 102 and are clamped in position on ways 103 by blocks 104, bolts 105 and nuts 106. Spring 107 serves to retain block 104 and bolt 105 in position controlled by the setting of nut 106, when releasing or clamping the guide boxes. The rest bars are secured to the main housing 19 of the traction apparatus on pads 108 and 109, by bolts 110 and nuts 111. These pads are shown in Figures 1 and 2 as well as Figures 20 through 24.

Referring now to Figures 15, 16 and 25, the traction apparatus 86 has the function to force a bar 5, indicated in Figure 25, into passes in driven mill rolls 112 and 113, which passes are

predicated on reductions in section area of such magnitudes as to preclude bar entry by tractive force of the rolls themselves. To prevent the bar 5 from buckling under the tractive force exerted by apparatus 86, guides 114 and 115 with idlers 116 are provided, which together with identical idlers 95 of delivery guides 91 serve to render lateral support to the bar at regular intervals between the runways 6, 6' of the traction apparatus (see Figure 11) and the mill rolls 112. The guides 114 are preferably fastened to a separate stand in front of mill rolls 112, while the guides 115 are held by customary guide boxes and rest bars, the latter attached to the housing for the rolls 112. Figure 25 further illustrates the manner of guiding and laterally supporting the bar in guides 91, 114 and 115.

With further reference to Figures 15 and 16, delivery guides 117 and entry guides 118 are preferably of the type illustrated in my co-pending application No. 531,724, Figures 18 through 22. In conjunction with guides 119, also of the cross section shown in Figure 18 of said application, they cover the space between mill rolls 112 and 113 and serve to keep the bar 5, now reduced to an oval section, from buckling under the longitudinal loading exerted by traction apparatus 86 in forcing bar entry into rolls 113. The delivery guides 120 of rolls 113 merely serve to direct the emerging bar with sufficient accuracy to bring its forward end within the bell-mouth of entry guides 121 of the next traction apparatus, indicated generally at 122. From there on and through mill rolls 123 and 124 and through traction apparatus 125, the bar guiding equipment is merely repeated with such modifications as called for by the changing size and shape of the bar.

Whereas the guides 117, 118 and 119 serve to 40 keep an oval section from buckling, they also serve to keep an oval bar from twisting on its own axis in the space between rolls 112 and 113, as required when employing my method for the reduction of hot rolled commercial rounds into cold rolled rounds of much smaller size and great accuracy. The latter function of guides 117 and 118, referred to in said co-pending application, is predicated on pass reductions of such magnitude that the oval produced from the commercial round can be made sufficiently pronounced, to permit of definite guiding and prevention of twist. In case of smaller reductions, the tendency to such twisting is correspondingly decreased and less detrimental to the accuracy of product. Furthermore, the cold and stiff bar 55 as a whole is held against turning on its own axis by the powerful gripping action of the traction apparatuses; a further insurance for accuracy of product.

It should be noted in this connection that the push exerted by traction of apparatus 86 continues until the forward end of the bar 5 is gripped in traction apparatus 122. From then on the apparatus 86 ceases to push and serves 60 instead to exert pull or back tension on the bar; all by speed control of traction apparatuses and mill rolls, now to be explained.

By nominally operating the traction belts of apparatus 86 at a speed somewhat below the entry speed of mill rolls 112 and those of apparatus 122 at a speed somewhat in excess of the corresponding continuous delivery speed of mill rolls 113, the bar 5 is held under tension between traction apparatuses while the driven mill 70 rolls 112 and 113 reduce its section area. By

duly controlling also the speeds of mill rolls 123 and 124 and of the traction belts of apparatus 125 with respect to traction apparatus 122, tension is also maintained on the bar in passage from apparatus 122 to apparatus 125 while driven mill rolls 123 and 124 further reduce its section.

It will be noted that the front end of each bar is reduced in mill rolls 112 and 113 without benefit of tension until the bar has advanced far enough to be gripped in traction apparatus 122. Also the rear end of each bar is reduced in these rolls without benefit of back tension, after it leaves the traction apparatus 86 and the mill rolls 112 respectively. This lack of tension and back pull will result in bars slightly over size at the ends. The performance is repeated in mill rolls 123 and 124, although the discrepancies are bound to be reduced rather than increased in these rolls due to smaller pass reductions. If bar requirements are merely for exact size within precision tolerances, I propose to cut the cold-rolled bar into required lengths and then to cold-reduce the over-sized end lengths to exact dimensions in either of the layouts shown in Figures 18 and 19 respectively and in a manner to be explained. If exacting quality requirements preclude such use of the end lengths, however, I propose to subject them to annealing for cold-reducing into bars of smaller size.

The layout shown in Figure 17 is predicated on cold reduction in driven mill rolls 126 and 127 and drawing to final size in die 128. Traction apparatuses 129 and 130 serve to push the forward ends of the bars into the roll passes and through the die respectively, and traction apparatus 131 furnishes the pull required for the drawing operation. Desired bar tension is maintained by speed control of traction belts and mill rolls. The purpose and construction of the guides shown in Figure 17 are evident from comparison with guides shown in Figures 15 and 16, the functions and construction of which have already been explained. Since the final size of the product is determined by the hole in the die, however, the tendency to twisting or turning of the bar, as above referred to, is now of minor importance and the product is of uniform section from end to end of bars.

Figure 18 shows my improved traction rolls 132 and 133 used respectively to push the forward ends of bars through the reduction passes of idler rolls 134 and 135 and to pull the bars through these passes, principally for the purpose of sizing of hot-rolled products. During the pulling operation, back tension on the bar between the traction rolls 132 and the idler rolls 134 can be maintained at any suitable figure, by speed control of the traction rolls 132. Since the pass reductions required are small and any tendency of the bar to turn in the roll passes is checked by the grip of the traction belts 136 and 137, the product is of accurate size from end to end of bars. In case the layout be used for extreme tolerance requirements, however, it may be necessary to divide the drawn product into suitable lengths and then to subject over-size end lengths to further treatment.

The layout shown in Figure 19 is predicated on sizing or cold-drawing in a single reduction. Traction apparatus 138 serves to force the forward ends of the bars through the die 139 to a point where these ends can be gripped by traction apparatus 140 for pulling the bars through the die. It also serves to furnish back pull on

the bars during the drawing operation, when suitable bar tension is established by speed control of the traction belts of apparatuses 138 and 140. The product is identical in size from end to end of bars. To attain larger reductions it is merely necessary to add required dies and traction means to the pass line.

The entry guides 141 of the traction rolls 132 and 133 are of the type described in connection with the tension rolls of my co-pending application above referred to, and the construction and purpose of other guides indicated in Figures 18 and 19 will be apparent by comparison with guides shown in Figures 15 and 16.

With respect to over-size end lengths above referred to, it will be understood that such lengths are partly of correct size but are over size at and near one end. The idea is to feed such lengths, good end first, through either of the layouts shown in Figures 18 and 19. In case of the former layout, the traction rolls 132 will push the bar through the passes of the idler rolls 134 and 135 and into the grip of traction rolls 133 without resistance, and the traction rolls 133 will then pull the bar through the passes to reduce its over-sized end portion to correct size, while the traction rolls 132 are caused to idle along. In case of layout shown in Figure 19, the traction apparatus 138 would push the good end of the bar through the die 139 with little or no resistance, and traction apparatus 140 would pull the over-sized end portion through the die to correct size.

With further reference to traction apparatus 35 and traction rolls (Figures 11, 15 and 18), pulleys 142 and 143 respectively provide for adjustment of belt tension to compensate for stretch or wear of traction belts 4, 4' and 136 and 137. Any conventional adjusting rigs may be used, and such a rig suited to pulleys 143 of the traction rolls is illustrated in my co-pending application above referred to. Idler sprockets 3, 3' should also be adjustable, in customary manner, to allow for desirable take-up of traction chains 1, 1'. Driving sprockets 2, 2' and idler sprockets 3, 3' should preferably be rubber mounted on respective shafts in any generally approved manner; the former to soften the shocks when the traction loads are applied to the bars by operation of the gripping drive, the latter to better accommodate the chain movements when the gripping drive is operated. These chain movements are otherwise compensated for by the end rollers of runways 6, 6' and the idler rollers 48, 48', which are mounted in anti-friction bearings and cushioned on rubber sandwiches as already explained.

It will be noted that the mill arrangements and layouts shown in Figures 16 through 19 permit of continuous operation, one bar following another without stoppage of mill rolls or traction belts, as close together as they can be fed to the traction apparatus or traction rolls.

Straight lengths of precision rounds may be produced from hot-rolled commercial rounds in cooling bed lengths or in coils. In the former case, suitable plant layouts are described and illustrated in my Patent 2,369,730 for Method of Rolling Metal Bars. By substituting appropriate mill arrangements or layouts of my present Figures 16 through 19 for mills 1, 12, 87 and 92 of Figures 11 and 12 of said patent, the handling of cooling bed lengths to the reduction mills and the disposition of the cold-reduced product is

readily understood. When cold-rolling or drawing from hot-rolled and coiled commercial rounds, the coil transfer, un-coiler and coil carrier described in my co-pending application above referred to, would serve to handle and open the coils and to feed the ends of the bars to any of the layouts of present Figures 16 through 19. The product is preferably handled in the manner called for in the same application with reference to its Figure 17.

Subject matter disclosed but not claimed in this application is claimed in my divisional applications Serial No. 9,508, filed February 19, 1948, and Serial No. 244,641, filed August 31, 1951.

Whereas my novel method of cold-reducing has been described with particular reference to rounds, one of the more difficult sections to roll to precise dimensions, it will be understood that my method lends itself equally well to precision cold-rolling or drawing of other sections.

It will be apparent that the tractive force of my novel apparatus is equally well suited for pushing a bar into a roll pass or through a hole in a die, if the stiffness of the bar against buckling be augmented by lateral supports to force the bar, into desired engagement and direction of travel, the pass reduction notwithstanding. In this manner I avoid the need for leaders, called for in said co-pending application.

I also provide a novel method for continuous cold-drawing of metal bars, not to my knowledge hitherto accomplished.

By using my traction apparatus on the entry as well as the delivery side of a roll pass or a die, desirable back tension can be maintained on the entering bar by speed control of the traction belts, to further lessen the work of bar deformation in the pass or die and prevent more rapid hardening of the metal.

In rolling from commercial rounds, the use of a traction apparatus on the entry side of the mill permits the bar to be held in the grip of the traction belts as it enters the mill, to keep it from turning in the roll passes. This is conducive (and in case of large reductions, essential) to accuracy of product.

I have also disclosed a novel method for recovery of over-sized end portions of bars reduced by my cold-rolling method, so that the scrap loss in cold reduction by any of the proceedings I have disclosed would be practically nil.

Although I have described certain preferred forms and practices of my invention, its advantages may be realized in other ways within the scope of the appended claims.

I claim:

1. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, positioning means predetermining the relative positions of the pressing devices and a connection between at least one of the mounting structures and the corresponding pressing device rapidly shiftable to dispose the

pressing devices in relative positions predetermined by the positioning means.

2. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, 5 mounting structures respectively disposed at least in part generally within the endless traction elements, pressing devices also respectively disposed at least in part generally within the endless traction elements behind said reaches thereof 10 respectively carried by the mounting structures and adapted to press said reaches toward each other, connecting means between at least one of the mounting structures and the corresponding pressing device movable to dispose the pressing devices in selected accurately predetermined 15 relative positions and a single operating element mechanically connected with the connecting means for operating the same to so move the pressing device.

3. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, 20 mounting structures respectively disposed at least in part generally within the endless traction elements, pressing devices also respectively disposed at least in part generally within the endless traction elements behind said reaches thereof 25 respectively carried by the mounting structures and adapted to press said reaches toward each other, connections between 30 at least one of the mounting structures and the corresponding pressing device movable to dispose the pressing device in selected accurately predetermined relative positions and a single operating element mechanically connected with the 35 connections to positively simultaneously operate the connections.

4. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, 40 mounting structures respectively disposed at least in part generally within the endless traction elements, pressing devices also respectively disposed at least in part generally within the endless traction elements behind said reaches thereof 45 respectively carried by the mounting structures and adapted to press said reaches toward each other, connecting means between one of the mounting structures and the corresponding pressing device, separate connecting means between the other of the mounting structures and the corresponding pressing device and means for simultaneously operating the first mentioned and second mentioned connecting means to simultaneously move the pressing devices toward or away from each other.

5. Traction apparatus for advancing elongated articles in the direction of the length thereof comprising two generally coplanar endless traction elements having respectively opposed substantially parallel reaches, means for driving the 55 elements so that at said reaches thereof they

move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, positioning means predetermining the relative positions of the pressing devices and a connection between each of the mounting structures and the corresponding pressing device rapidly shiftable to alter the distance between the pressing devices.

6. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, crank means connecting at least one of the mounting structures and the corresponding pressing device and means operating the crank means to alter the distance between the pressing devices.

7. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, a pair of similar generally parallel cranks connecting at least one of the mounting structures and the corresponding pressing device and means for simultaneously operating the cranks to alter the distance between the pressing devices.

8. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, a plurality of cranks connecting at least one of the mounting structures and the corresponding pressing device and means moving the pressing device relatively to the mounting structure to cause turning of the cranks and consequent alteration of the distance between the pressing devices.

9. Traction apparatus for advancing elongated articles in the direction of the length thereof

comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, a plurality of cranks connecting each of the mounting structures and the corresponding pressing device and means simultaneously moving both pressing devices, each relatively to the corresponding mounting structure, to cause turning of the cranks and consequent simultaneous movement of the pressing devices toward or away from each other.

10. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, a connection between at least one of the mounting structures and the corresponding pressing device rapidly shiftable to dispose the pressing devices in selected accurately predetermined relative positions and means for adjustably positioning at least one of the mounting structures toward and away from said reaches of the endless traction elements.

11. Traction apparatus for advancing elongated articles in the direction of the length thereof comprising two generally coplanar endless traction elements having respectively opposed substantially parallel reaches, means for driving the elements so that at said reaches thereof they move in the same direction at the same speed, mounting structures respectively disposed at least in part generally within the endless traction elements, pressing devices also respectively disposed at least in part generally within the endless traction elements behind said reaches thereof respectively carried by the mounting structures and adapted to press said reaches toward each other, connecting means between one of the mounting structures and the corresponding pressing device, separate connecting means between the other of the mounting structures and the corresponding pressing device, means for simultaneously operating the first mentioned and second mentioned connecting means to simultaneously move the pressing devices toward or away from each other and means for adjustably positioning each of the mounting structures toward and away from said reaches of the endless traction elements.

12. Traction apparatus for advancing elongated articles in the direction of the length thereof comprising two generally coplanar endless traction elements having relatively opposed substantially parallel reaches, means for driving the elements so that at said reaches thereof they move in the same direction at the same speed, mounting structures respectively disposed at least

15

in part generally within the endless traction elements, pressing devices also respectively disposed at least in part generally within the endless traction elements behind said reaches thereof respectively carried by the mounting structures and adapted to press said reaches toward each other and separate means for adjustably positioning each of the mounting structures toward and away from said reaches of the endless traction elements.

13. Traction apparatus for advancing elongated articles in the direction of the length thereof comprising two generally coplanar endless traction elements having relatively opposed substantially parallel reaches, means for driving the elements so that at said reaches thereof they move in the same direction at the same speed, supporting means, mounting structures respectively disposed at least in part generally within the endless traction elements and supported by the supporting means, pressing devices also respectively disposed at least in part generally within the endless traction elements behind said reaches thereof respectively carried by the mounting structures and adapted to press said reaches toward each other and means including a slideable wedge block wedgingly engaged between the supporting means and at least one of the mounting structures for adjustably positioning the mounting structure relatively to the supporting means.

14. Traction apparatus for advancing elongated articles in the direction of the length thereof comprising two generally coplanar endless traction elements having relatively opposed substantially parallel reaches, means for driving the elements so that at said reaches thereof they move in the same direction at the same speed, supporting means, mounting structures respectively disposed at least in part generally within the endless traction elements and supported by the supporting means, pressing devices also respectively disposed at least in part generally within the endless traction elements behind said reaches thereof respectively carried by the mounting structures and adapted to press said reaches toward each other, a plurality of adjustable connections between the supporting means and at least one of the mounting structures and means for simultaneously operating

said connections for adjustably positioning the mounting structure relatively to the supporting means.

15. Traction apparatus for advancing elongated articles in the direction of the length thereof comprising two generally coplanar endless traction elements having relatively opposed substantially parallel reaches, means for driving the elements so that at said reaches thereof they move in the same direction at the same speed, supporting means, mounting structures respectively disposed at least in part generally within the endless traction elements and supported by the supporting means, pressing devices also respectively disposed at least in part generally within the endless traction elements behind said reaches thereof respectively carried by the mounting structures and adapted to press said reaches toward each other, a plurality of adjustable connections between the supporting means and at least one of the mounting structures, each of said connections including wedge means and screw means for operating the wedge means, and means for simultaneously operating the screw means to adjustably position the mounting structure relatively to the supporting means.

GUSTAF L. FISK.
